(57) **CLAIM**

The ornamental design for a sun lounger, as shown and described.

DESCRIPTION

FIG. 1 is a front perspective view of the sun lounger of the present invention;

FIG. 2 is a left-side view thereof;

FIG. 3 is a right-side view thereof;

FIG. 4 is a front view thereof; and,

FIG. 5 is a top plan view thereof.

The broken lines depicting internal mechanical elements and footers of the sun lounger form no part of the claimed design.
